UNITED STATES PATENT OFFICE

158,233

ADJUSTABLE RADIO AND TELEVISION
ANTENNA

Charles A. Trowbridge, Roxborough, Pa., assignor
to Ontario Research Corporation, Philadelphia,
Pa., a corporation of Pennsylvania

Application April 28, 1949, Serial No. 2,310

Term of patent 3½ years

(Cl. D26—14)

To all whom it may concern:

Be it known that I, Charles A. Trowbridge, a citizen of the United States, residing in Roxborough, Philadelphia County, Pennsylvania, have invented a new, original, and ornamental Design for Adjustable Radio and Television Antenna, of which the following is a specification, reference being had to the accompanying drawings, forming a part thereof, in which:

Fig. 1 is a perspective view of an adjustable antenna showing my new design with the antenna arms thereof adjusted in one position;

Fig. 2 is an end elevational view of the adjustable antenna on a scale enlarged over that of Fig. 1 and with the antenna arms thereof in vertical position;

Fig. 3 is a side elevational view thereof with the antenna arms broken away for purposes of illustration; and

Fig. 4 is a plan view thereof.

I claim:

The ornamental design for an adjustable radio and television antenna, substantially as shown and described.

CHARLES A. TROWBRIDGE.
